UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed August 2, 1921. Serial No. 489,292.

To all whom it may concern:

Be it known that I, ARVID H. NERO, a citizen of the United States of America, residing at New Britain, in the county of Hartford and State of Connecticut, have invented 5 certain new and useful Improvements in Electric Switches, of which the following is a specification.

My invention relates to electric switches, 10 and particularly to a switch for electric lamp sockets, the object of my invention being to provide a simple and effective switch mechanism affording a quick make and break of the circuit, and capable of safely handling a relatively heavy current.

The invention also comprises certain features of improvement in general construction and arrangement of parts hereinafter described or illustrated in the accompanying 20 drawings, in which

Fig. 1 is a broken plan of the body of an electric lamp socket in which my invention is embodied in one form;

Fig. 2 is a plan view with the top portion 25 of the insulating body removed and showing the switch elements in different positions;

Fig. 3 is a section on the line 3—3, Fig. 1;

Figs. 4 and 5 are sections on the lines 30 4—4 and 5—5 respectively, Fig. 3;

Fig. 6 is a section on the line 6—6, Fig. 1; and

Fig. 7 is a section on the line 7—7, Fig. 2.

While the present switch mechanism may 35 be applied to electric switches of various sorts, I have for convenience illustrated it in an electric lamp socket. As here shown the socket comprises an insulating body having insulating buttons 10 and 11 united by 40 through screws 12 and 13. The button 11 is recessed on its meeting face to afford a switch chamber 14 and channel 15, through which passes the rotary spindle 16 on which is mounted the exterior actuating thumb 45 piece 17.

Mounted on the outer face of the button 11 is the usual screw shell 18 of the lamp socket, the base flange of which is overlaid by the yoke 19 tapped to receive the holding screws 12 and 13 which thus not only 50 unite the buttons, but also secure the screw shell in position on the socket body. The yoke 19 is provided with an offset lug 20 which passes through an aperture 21 in the base 55 of the screw shell and lies in an exterior

channel 22 formed in the sides of the buttons 10 and 11. At a suitable point it is tapped to receive the binding screw 23, by which a lead wire may be secured and the current thus led from one of the mains directly to the screw shell.

On the opposite side of the body, the buttons 10 and 11 are recessed at 24 to receive the terminal strap 25 carrying the binding screw 26 for the other lead wire, 60 and having its base offset to receive a holding screw 27. Beneath the head of the latter is engaged the foot piece 28 of the switch contact 29 which passes through a hole 30 in the button 11 and rests against the wall 70 of the switch chamber in one corner of the latter. A second switch contact 31 lies in the adjacent corner of the chamber on the opposite side of the switch spindle 16 and passes through a similar hole 30 in the button 11 to the outer face of the latter, where it is offset to form the center contact 32 of the socket. A screw or rivet 33 passing through the body of the center contact 32 engages a countersunk nut 34 in the switch 75 chamber, or has its inner end riveted over at this point to secure the center contact in position.

To make or break the circuit between the switch contacts 29 and 31, I provide a U-shaped switch bar 35 freely mounted on the rotary spindle 16 and carried by a spring yoke 36, the arms 37 and 38 of which straddle the actuating slide plates 39 and 40. The latter are provided with offset lugs 80 pivoted on pins 41 and 42, which may be conveniently formed as lugs on opposite sides of the frame 43. The base of the frame is let into a suitable recess in the bottom of the switch chamber 14 and is secured by the screw 44 passing through the button 11, and having its head countersunk beneath the center contact 32. At right angles to the pins 41 and 42 are standards 45 and 46, in which the spindle 16 is journaled. At 85 this point the spindle is provided with flats, with which engage the cams 47 and 48, at right angles to each other on the spindle and spaced apart by a hollow bushing 49. The spindle may be secured in the frame in any suitable manner, as by the cotter pin 50 passing through a hole in the end of the spindle projecting beyond the standard 45. 90 In order to steady the frame and the pivot pins 41 and 42, holes 51 and 52 are formed 105 95 110

in the inner face of the button 10. Clearance recesses 53 and 54 are also formed in this button to accommodate the cams 47 and 48 during their rotation. The slide plates 39 and 40 as well as the switch bar 35 are retained in position by the button 10, which not only prevents the slides from escaping the pins 41 and 42, but also prevents the switch bar and spring yoke from turning 10 with the switch spindle.

The operation of the switch is readily understood. Assuming the switch to be in the circuit-closing position indicated in Fig. 1, the thumb piece 17 is turned either clockwise or contra-clockwise. As it rotates it carries with it the cams 47 and 48, which are fast thereon. The latter bear upon the inner faces of the slide plates 39 and 40, which lie on opposite sides of the spindle. 15 Consequently, as the spindle rotates, the cam 47 moves out of the path of the ends of the slide plates on one side of their axes, while the cam 48, bearing against the ends of the slide plates on the opposite side of their 20 axes, rock them to the position shown in Fig. 2. As the ends of the slide plates adjacent the switch bar move apart, they spread the spring legs 37 and 38 of the yoke 36 and place the latter under greater tension. 25 As soon therefore as the slide plates have been shifted by the cam 48 to an inclination opposite to that which they occupy in Fig. 1, the spring legs 37 and 38 of the yoke, tending to approach each other, slide 30 down these inclines to the position shown in Fig. 2. This results in the longitudinal shifting of the yoke and the associated switch bar on the spindle 16, which moves with a snap action from the circuit-closing 35 position of Fig. 1 to the circuit-breaking position of Fig. 2. A double break in the circuit is thus effected.

Various modifications in details of construction and operation will readily occur 40 to those dealing with the problem, without departing, however, from what I claim as my invention.

I claim:

1. An electric switch having a pair of 45 spaced contacts, a spring-yoke switch bar, a pair of pivoted slide plates embraced by said spring yoke, and rotary cam means for simultaneously rocking said slide plates in opposite directions to tension and bias said 50 spring yoke and thereby impart rectilinear movement to the switch bar to make or break connection with the switch contacts.

2. An electric switch having a pair of 55 spaced contacts, a spring-yoke switch bar, a pair of pivoted slide plates embraced by said spring yoke, and cam means rotatable in either direction to simultaneously rock

said slide plates in opposite directions to tension and bias said spring yoke and thereby impart rectilinear movement to the switch 60 bar to make or break connection with the switch contacts.

3. An electric switch having a pair of spaced contacts, a spring-yoke switch bar, a rotary switch spindle on which the switch 65 bar element is guided for rectilinear movement, a pair of pivoted slide plates embraced by said spring yoke and lying on opposite sides of the switch spindle, and means on the spindle to engage and rock 70 said slide plates simultaneously in opposite directions on the rotation of the spindle whereby said spring yoke is tensioned and biased, thereby imparting rectilinear movement 75 to the switch bar to make or break connection with the switch contacts.

4. An electric switch having a pair of spaced contacts, a spring-yoke switch bar, a rotary switch spindle on which the switch 80 bar element is guided for rectilinear movement, a pair of pivoted slide plates embraced by said spring yoke and lying on opposite sides of the switch spindle, and means on the spindle to engage and rock 85 said slide plates simultaneously in opposite directions on the rotation of the spindle in either direction whereby said spring yoke is tensioned and biased, thereby imparting rectilinear movement 90 to the switch bar to make or break connection with the switch contacts.

5. In an electric switch, a switch chamber having an end wall, a rotary switch spindle passing through said wall, a pair of switch 95 contacts resting against said wall on opposite sides of the switch spindle, a reciprocating spring-yoke switch bar guided on said spindle and cooperating with said contacts, a pair of pivoted slide plates embraced by said spring yoke and means operative, 100 on the rotation of the spindle, to rock said slide plates in opposite directions thereby to tension and bias said spring-yoke switch bar to make or break connection with the switch contacts.

6. An electric switch comprising a rotary switch spindle, a pair of cams thereon, a pair of slide plates operatively associated with said cams and arranged on opposite sides of said spindle and mounted on axes 115 at right angles to the switch spindle, together with a yoke having spring legs embracing the slide plates and biased by the 120 rocking of the latter on rotation of the switch spindle and cams.

In testimony whereof I have signed my name to this specification.

ARVID H. NERO.
